CARPULE FILLING MACHINE

Norman Applezweig, New York, N. Y.

Application December 21, 1944, Serial No. 569,124

3 Claims. (CL 226—116)

1
This invention relates to an apparatus for filling carpules, "carpule" being the term employed herein to denote a hermetically sealed fluent receptacle of the type adapted for use in a cartridge syringe.

It is an object of the invention to provide an inexpensive machine comprising relatively few and simple parts, which is adapted to fill carpules automatically, quickly and accurately.

It is a more specific object of the invention to provide a carpule filling machine in which carpules are mechanically led to and beyond a filling station where a filling mechanism automatically injects fluent material into the carpules, so that no individual manual handling of the carpules is required for filling.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the claims.

In the accompanying drawings, in which is shown one of the various possible embodiments of this invention,

Fig. 1 is a top plan view of a carpule filling machine embodying my invention;

Fig. 2 is a sectional view therethrough, taken substantially along the line 2—2 of Fig. 1, and in addition schematically showing the source of filling fluid;

Fig. 3 is a fragmentary enlarged side view of the machine;

Fig. 4 is an enlarged sectional view taken substantially along the line 4—4 of Fig. 3; and

Fig. 5 is a fragmentary view similar to Fig. 4 but showing the machine at a later stage of its operation.

Essentially, the apparatus shown and described herein comprises a filling station F, means M to move carpules to and beyond the filling station, an injecting means I at said station of the proper type to fill a carpule, means D to dispose the carpules in predetermined relationship to the injecting means when the carpules are at the filling station, and means S to shift said injecting means toward and away from filling position.

Carpules require a special type of injecting or filling means, due to their particular construction. In general, this construction comprises an open-ended tube 12 (Figs. 4 and 5) which is hermetically sealed at both ends, being closed at one end by a cap 14 of self-sealing material such as

2
rubber, and at the other end by a plug 16' of resilient material. The term "self-sealing" as used herein denotes the ability of the material of the cap to close hermetically a small hole left in it by passage therethrough of a slender tube such as a hypodermic needle. The plug is adapted to be forced toward the cap when the carpule is used in a cartridge syringe. The cap 14 has a thin zone 16 which is adapted to be pierced by one of the two needles of a conventional cartridge syringe. Said cap has a flange 18 which abuts against the rim at one end of the tube 12 to prevent the cap from being forced into the carpule after being properly positioned. Carpules are furnished for filling in sterile, empty, hermetically closed condition, i. e., with both ends closed, as indicated, the gaseous atmosphere within the carpule being at or about atmospheric pressure. Because of this construction, when carpules are filled with a fluent material, e. g. a pharmaceutical liquid, the gas which is displaced must be allowed to leave the carpule, so that the carpule filling means employed herein essentially includes two conduits—one to lead fluent material into the carpule, and the other to permit escape of the displaced atmosphere.

Referring now in detail to the drawings, 10 denotes a machine embodying my invention and comprising a frame 20 on which the various machine elements are supported. Running along the two sides of the frame on the upper face thereof are a pair of angle irons 22 spaced apart far enough to act as rails for slidably receiving racks 24 forming part of the means M to move the carpules to and beyond the filling station F.

Each rack includes a base plate 26 having a series of carpule holding means 28 secured to its upper surface. These carpule holding means may, as illustrated, be in the form of tubes attached at their lower ends to the plate 26 and having their upper ends 30 open and flanged to facilitate insertion of carpules therein. Said carpule holding means are arranged in rows longitudinally and transversely of the plate, the term "longitudinally" as used herein denoting the direction of travel A of carpules through the machine. The number of carpules in each transverse row corresponds to the number of individual injecting means at the filling station, and the number of carpule holding means in each longitudinal row may vary, several carpule holding means preferably being provided in each longitudinal row to obtain the full benefit of using racks such as described.

Many such racks 24 are employed, as in the

operation of the machine empty carpules are inserted plug-down in the carpule holding means 28 of a rack 24 while the same is remote from the filling machine 10, and the loaded rack then placed on rails 22 at the receiving end R of the machine. After all the carpules in a rack have been filled, the entire rack is lifted from the rails at the discharge end D of the machine.

The means to move the carpules to and beyond the filling station also includes a pair of endless chains 32, one on each side of the machine 10, running through the space between the rails 22 from a point adjacent the receiving end R of the machine to and beyond the filling station F. The chains are connected at regular intervals by strips 34, having pusher flanges 36 which are adapted to engage the trailing edges 38 of racks 24. With this construction, if the upper reaches of the chains are moved in the direction indicated by the arrow A, the pusher flanges 36 will force the racks 24 to move in like direction through the machine.

Suitable means is provided for moving the chains in such direction, and since, as will later be seen, the filling station F is stationary, said means desirably is adapted to impart an intermittent motion to the chains whereby the carpules may be held stationary during filling. The chain moving means includes two pairs of sprockets 40, 40', one pair on each side of the filling station F, so that the chains can move the racks to and beyond said station. Each pair of sprockets is interconnected by a shaft 42, 42' so as to synchronously move the chains. The shaft 42' beyond the filling station F projects from the frame 20 and carries a Geneva wheel 44. This Geneva wheel consists of a disc 46 having a plurality of radial slots 48 formed therein. Intermediate the slots, the circumference of the disc is provided with concave locking segments 50. The wheel is intermittently turned by a crank pin 52 mounted on a crank plate 54 secured for rotation on a shaft 56 which is driven continuously from any suitable source of power. The crank plate has a segmentally circular flange 58 which slidably engages the locking segments 50 when the pin 52 is not traveling in one of the radial slots 48. This arrangement holds the Geneva wheel stationary between its periods of intermittent motion. The Geneva wheel is so dimensioned with respect to the diameter of the sprockets 40 that each time said wheel turns through 90° the chains 32 will move a distance equal to that between the centers of adjacent carpule holders 28 in a longitudinal row.

Both the Geneva wheel and the crank plate are secured to their respective shafts 42', 56 by suitable means, such as set screws (not shown), which permit simultaneous adjustment of the gear and plate in such manner that the chain moving means may be arranged to place a transverse row of carpule holding means 28 in registry with the injecting mechanisms I at the feeding station F during the idling periods of the chains.

The feeding station F includes two vertical standards 60, 62, one fixed at each side of the machine, these standards being adapted to shiftably support the injecting means I and the means D to dispose the carpules in predetermined relationship to said injecting means.

The means D for disposing the carpules in such relationship comprises a frame 64 extending between the two standards 60, 62 and having ends 66 slidably but non-rotatably received

in vertically extending slots 68 in said standards. Said frame carries a plurality of positioning sleeves 70 whose lower ends 72 are flared and whose upper ends have flanges 73 defining central apertures 74. The inner diameter of each sleeve is slightly greater than the external diameter of the carpule caps 14. The frame 64 is provided with a large through opening 76 at each end for a purpose soon to be apparent. A cam-following roller 78 is rotatably mounted on each end of the frame 64, said rollers resting under gravity on cams 80, one on each side of the machine. Said cams are fixed to shafts 82 journaled in pedestals 84 secured to the frame 20. These shafts carry sprockets 86 driven by chains 87 which mesh with sprockets 88 of the same size as the sprockets 86. One sprocket 88 is fixed to the driveshaft 56. The chains 87 are interconnected for synchronous movement by a sprocket 89 and a countershaft 92 which carries the other sprocket 88. By virtue of this construction, each time the shaft 56 turns once, the frame 64 will be raised and lowered once. The several positioning sleeves 70 are in such relationship to the frame of the machine that each sleeve 70 is in alignment with one of the longitudinal rows of carpule holding means 28.

Each injecting means I at the feeding station comprises an elongated barrel 94 screwed into a frame 96 extending between the standards 60, 62. Said barrel has an axial bore 98 running from end to end and enlarged at the upper end to provide a recess 100 leading to a conical seat 102. An outlet arm 104 for coupling to a resilient tube is integrally fashioned on one side of the body, said arm having a central bore 106 which is connected to the longitudinal bore 98 of the barrel. The barrel also has a threaded tip 108 of small diameter on which there is screwed the hub 110 of a slender hollow needle 112, such as a hypodermic needle. It will be obvious that this needle is connected by the bore 98 to the outlet bore 106. The needle 112 is disposed in alignment with the aperture 74 in its associated carpule positioning sleeve 70 and with the thin zones 16 of carpule caps successively held thereby.

Each individual injecting means I also includes a second hollow slender needle 114 which is adapted to be thrust through said thin cap zone 16 so that as a fluent material is fed into a carpule through one of the needles, for example, the inlet needle 114, the displaced gas within the carpule may be led off through the outlet needle 112. Although any mounting of the two hollow needles 112, 114 which enables them to pierce the cap is satisfactory, I prefer to have said needles coaxially disposed so that they jointly will pierce but a single hole in the cap. Accordingly, as shown in Figs. 4 and 5, the inlet needle 114 is small enough to be received in the outlet needle 112 and permit passage of gas or effluent through the needle 112 and bore 98.

Even more satisfactory results may be obtained by having the outer needle 112 pierce the carpule cap first and, after this initial piercing has taken place, moving the tip of the inner needle to a position below the tip of the outer needle. Such operation may be secured by mounting the needle 114 for vertical, freely-slidable movement within the needle 112 and having the needle 114 offer such slight resistance to movement away from a carpule that when the tip of the needle 114 rests on a carpule cap, said needle will not pierce said cap but will only enter a carpule after the cap thereof has been pierced by the needle 112.

Downward movement of the needle 114 is ensured by weighting the same with a fixture 116 designed to couple the needle 114 to a resilient conduit. The weight of this fixture is not enough to force the needle 114 through a carpule cap. The fixture 116 has a conical plug 118 on its lower surface designed to fit snugly, the conical seat 102 and seal the bore 98 when the injecting mechanism is in operation. This is necessary since the filling system works either above or below atmospheric pressure and its operation would be disturbed if said system were open to the air.

It may be mentioned that, if desired, the needle 114 can be urged to its outthrust position by a spring instead of gravity.

All the coupling fixtures 116 are connected by short lengths 120 of resilient tubing, a distributing manifold 122, and an inlet pipe 124 to a source of supply such as a bottle 126 containing fluid material with which it is desired to fill the carpules. All the coupling arms 104 are connected by short lengths of resilient tubing 126 to an exhaust manifold 128 running into an outlet pipe 130. Said pipe extends to a suction pump 132 comprising, by way of example, the barrel 134 of a large hypodermic syringe and two check valves 136, 138, one on each side of the syringe. Both check valves permit flow of fluid only away from the filling station. Thus, when the plunger of the syringe is lifted the valve 138 will close and a sub-atmospheric pressure will be established in the exhaust manifold 128. When the needles 112, 114 are in the filling position illustrated in Fig. 5, this will draw fluid from the bottle 126. On the downstroke of the plunger the check valve 136 will close and fluid compressed under the plunger will be forced past the check valve 138.

It may be desirable, particularly when air bubbles are to be removed from the carpules, to return the outlet pipe 130 to the bottle 126, and, accordingly, I have provided a pipe 140 connecting the check valve 138 to said bottle. It will be observed that said pipe 140 terminates in the bottle above the level of the liquid 142 therein, although the pipe 124 terminates close to the bottom of said bottle. In this manner, any fluid returning through the outlet pipe will be pumped back into the bottle.

It may be mentioned that instead of employing a suction pump in the outlet pipe, a pressure pump could be placed in the inlet pipe 124, as illustrated in dotted lines by the pump 146. In such case, however, as will later be seen, it is necessary to provide control means, such as electric switches, to intermittently operate the electric motor M' which drives the pump 146. On the other hand, where a pump is placed in the outlet line, the electric motor M for said pump 132 may be operated continuously, since as will shortly be apparent, liquid then will only be pulled out of the bottle 126 when the needles 112, 114 have entered a carpule.

The means S to shift the injecting means I from its idle position shown in Fig. 5 to its filling position shown in Fig. 5 includes the frame 96 whose ends 148 are slidably but non-rotatably received in the vertical slots 68 of the standards 60, 62. Each of said ends carries a roller 150 riding on a cam 152, fixed to a shaft 154. Said shafts are journaled in the pedestals 84 and carry gears 156 meshing with gears 158 on the shafts 82. The gears 156, 158 are of the same size, so that the shafts 156 will turn once for each revolution of the shafts 82. The rollers 78

150 are maintained in contact with the cams 152 by the weight of the frame 96 and by pull springs 159 tensioned between the two ends of said frame 96 and the machine frame 20 and passing through the apertures 76 in the frame 64.

The cams 80 are so designed that the carpule positioning sleeve frame 64 will begin to move downwardly as locking segment 50 is engaged by the flange 58. At such time a transverse row 10 of carpules is disposed at the feeding station F with each carpule directly beneath a positioning sleeve. The frame 64 is moved downwardly until the flange 73 of each sleeve rests on the cap 18 of the carpule located therebeneath. As 15 the shafts 82 continue to turn, the cams 80 will leave the roller followers 78, whereby the full weight of the frame 64 rests on the several carpules in said transverse row. It will be noted that due to the non-rotatable mounting of the frame ends 66 in the standards 60, 62, said frame will have no tendency to turn as it rests upon the carpules, so that the carpules are firmly and accurately held in place preparatory to and during the filling thereof.

25 The cams 152 are so designed with respect to the cams 80 that the tips of the inner hollow needles 112 will touch the carpule caps 18 after the positioning frame 64 has come to rest. Immediately thereafter, the tips of the needle 112 pierce the thin zones 16 in the caps under the weight of the frame 96 and the pressure exerted by the springs 159. As soon as the needles 112 pierce the carpule caps, the needles 114 descend by gravity to assume their filling position. At 30 this point the cams 80 and 152 are provided with low dwells, so as to permit the sleeves 70 to remain in engagement with the carpules and the needles 112, 114 to stay in filling position.

During filling, the manifold 128 is under sub-atmospheric pressure because of the continuous 40 operation of the pump 132. This creates a sub-atmospheric pressure in the carpules. The pressure in the bottle 126 is atmospheric, due to the provision of a vent 160. The liquid in the bottle will, therefore, rise through feed line 124 to flow into the distributing manifold 122, from whence it enters the needles 114 and passes into the several carpules. The low dwells of the cams 80, 152 are so designed that after a sufficient 45 period of time has elapsed to fill the carpules under the prevailing conditions, first the injecting means I is raised, and then the positioning frame 64. Disengagement of the tips of the needles 112 from the carpule caps will prevent any more liquid from being sucked into the carpules, since a sub-atmospheric pressure will no longer be maintained in said carpules. No liquid will drip from the capillary bore of either needle 112, 114.

50 In the event that a pump is used in the feed line 124, suitable electric switches are placed in the path of the barrel 94 and a fixture 116 and another switch in the path of the racks 24 at the feeding station so that the motor M' will be turned on only when the holding means and filling means are in filling position and carpules are at the filling station.

55 As soon as the frames 64 and 96 have been raised to their uppermost positions (Fig. 4), the flange 58 will disengage a locking segment, the pin 52 will enter a slot 48, and the rack 24 will be advanced a distance equal to the space between the centers of adjacent carpules in the same longitudinal row. While the racks are advancing, the rollers 78, 150 ride on high dwells

of the cams 80, 152 which maintain the frames 64 and 96 in elevated position out of the path of the next transverse row of carpules.

Adjacent strips 34 are spaced apart a distance equal to an integral multiple of the spacing between carpule centers. However, there may be a space between adjacent racks at which the filling means will descend despite the absence of carpules. It will be appreciated that when this occurs, no filling fluid flows through the needle 114 because either the switch designed to be engaged by a rack at the filling station is not closed, or if the suction pump 132 is employed, no suction is applied from a needle 112 to a needle 114 through a carpule.

It will thus be seen that there is provided an apparatus for filling carpules which achieves the several objects of this invention and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. For use at the filling station of an apparatus for loading hermetically sealed carpules, each of which is closed by a cap of self-sealing material, and which apparatus includes means for moving carpules to and beyond said filling station, and for holding carpules in proper position for load-

ing at said station: an injecting means including a pair of hollow slender coaxial needles, one slideable telescopically disposed within the other, means for urging the inner needle to a normal position wherein its tip is below the tip of the outer needle, and means to move said needles axially toward and away from the cap of a carpule stationarily disposed at said station between two extreme positions, in one of which the tips of both of said needles extend through said cap and in the other of which both said tips are outside of said receptacle.

2. An apparatus as set forth in claim 1 wherein the inner needle is urged by gravity to the normal position wherein its tip is below the tip of the outer needle.

3. A combination as set forth in claim 1 wherein means is provided to supply a fluent filling material under atmospheric pressure to the inner needle, and wherein means is provided to establish a sub-atmospheric pressure in the outer needle.

NORMAN APPLEZWEIG.
